UNITED STATES PATENT OFFICE.

HERMAN NIELSEN, OF EDGERTON, WISCONSIN.

STEAM-ENGINE.

SPECIFICATION forming part of Letters Patent No. 530,961, dated December 18, 1894.

Application filed July 13, 1894. Serial No. 517,456. (No model.)

To all whom it may concern:

Be it known that I, HERMAN NIELSEN, a citizen of the United States, residing at Edgerton, in the county of Rock and State of Wisconsin, have invented a new and useful Steam-Engine, of which the following is a specification.

This invention relates to steam engines; and it has for its object to effect certain improvements in engines of the rotary type wherein a head or pressure of steam shall be utilized to its fullest extent, thereby securing the greatest possible amount of power therefrom.

To this end the main and primary object of the present invention is to provide a new and useful engine of the character noted constructed of comparatively few parts while at the same time having every adjustment necessary to insure a positive and efficient operation.

With these and other objects in view, which will readily appear as the nature of the invention is better understood, the same consists in the novel construction, combination, and arrangement of parts hereinafter more fully described, illustrated, and claimed.

In the accompanying drawings:—Figure 1 is a perspective view of a steam engine constructed in accordance with this invention.

Fig. 2 is a central vertical longitudinal sectional view thereof. Fig. 3 is a vertical sectional view on the line $x-x$ of Fig. 2. Fig. 4 is a similar view on the line $y-y$ of Fig. 2. Fig. 5 is a side elevation of the revolving cylinder wheel with the side cap plate removed showing the radially disposed steam cylinders therein. Fig. 6 is a detail in perspective of the adjustable valve ring detached. Fig. 7 is an inner side elevation of the valve ring and the disk on which it turns. Fig. 8 is a detail in perspective of the crank shaft and shaft block.

Referring to the accompanying drawings, 1 designates a bearing bracket that is adapted to be suitably supported on any convenient supporting frame or stand for the engine, and said bearing bracket is provided with the opposite parallel bearing arms 2, having squared sockets 3, in their upper ends and adapted to support for rotation there-between the revolving cylinder or casing wheel 4, from

which motion may be communicated by a belt or other suitable means to any machinery that is designed to be driven from the engine. The said revolving cylinder or casing wheel 55 4, is closed at one side and at its open side is adapted to be removably inclosed by the removable side cap plate 5, which serves to firmly position within the wheel, the steam cylinders 6. The steam cylinders 6, are arranged inside of the wheel radially to the center thereof, and are spaced equally distant from each other. The said cylinders 6, are securely clamped in their regularly spaced and radially disposed positions by means of 65 the segmental clamp plates 7, interposed between the cylinders and clamped tight against one side of the same by means of the clamp screws 8, passing through such plates and engaging threaded openings in the closed sides 70 of the revolving cylinder or casing wheel.

The radially disposed steam cylinders 6, are open at their inner ends and are provided in their outer closed ends and at the side next to the closed side of the wheel 4, with the steam ports 9, that provide for the admission of steam into the cylinders and the exhaust of steam therefrom, and said ports 9, communicate with the channel plates 10, that are placed between said cylinders and the closed 75 side of the cylinder or casing wheel, and also communicate with the side steam ports 11, which pierce the closed side of said wheel 4, at a point nearer the center of the wheel than the location of the ports 9, there being one of 80 the ports 11, for each cylinder 6, to provide for the admission of steam thereto and the exhaust therefrom. The said ports 11, correspond in arrangement and disposition to the cylinder ports with which they communicate in order that provision may be made 85 for feeding one pair of cylinders and for exhausting the directly opposite pair at the same time.

The inner open ends of the cylinders 6, accommodate the movements of the solid piston heads 12, and the piston rods 13, pivotally connected at their outer ends as at 14, to the inner sides of said piston heads, and the other inner ends of said piston rods are 90 pivotally centered on the upwardly disposed crank or crank pin 15, of the stationary crank 100

shaft 16. The stationary crank shaft 16, projects through a central bearing opening 17, in the side cap plate 5, of the revolving cylinder wheel to form a bearing support for that 5 side of the wheel, and the outer end of said stationary crank shaft has fitted thereto the squared shaft block 18, that is adapted to fit in the squared socket 3, at the upper end of one of the bearing arms 2. The squared 10 shaft block 18, is provided with a depending screw plate 19, having a screw opening 20, to receive a securing screw 21, passing therethrough and through an aligned opening in a U-shaped washer plate 22, embracing the block 18, and interposed between the plate 19, and the adjacent bearing arm. The screw 21, engages a threaded opening 23, in one of said bearing arms and serves to securely 15 clamp the block 18, firmly in position to maintain the crank shaft perfectly stationary. By reason of the support for the cylinder wheel described, it will be obvious that the steam which is admitted into the cylinders 6, to operate upon the pistons therein will transmit 20 a rapid rotation to the cylinder or casing wheel carrying the cylinders, the rotation of such wheel changing the position of the ports 11, so that the proper feed and exhaust of the steam will occur in the manner to be described. The said revolving cylinder or casing 25 wheel 4, has projected from its closed side in which the ports 11, are formed a central bearing trunnion 24, that loosely turns in one end of the bearing sleeve 25, squared 30 or reduced at opposite sides as at 26, to fit in the squared socket at the upper end of one of the bearing arms 2, in order to be held stationary. The said bearing sleeve 25, is provided at its inner end with the integral or 35 fixed bearing disk 28, the periphery of which is beveled and is provided with directly opposite steam recesses 29, with the upper of which is connected one end of the live steam pipe 30, and with the lower of which is connected one end of the exhaust steam pipe 31. 40 The said peripherally beveled stationary bearing disk 28, accommodates for movement thereon the adjustable valve ring 32. The adjustable valve ring 32, has its inner periphery beveled reversely to the periphery of the disk 28, so that the said ring cannot work 45 off of the bearing disk on which it is mounted when the various parts of the engine are set up.

50 The adjustable valve ring 32, is adapted to fit the closed side of the revolving wheel 4, in a steam tight joint, and upon its inner side contacting with the said revolving wheel, the valve ring is provided with diametrically opposite segmental steam grooves 33, which are sufficiently long to connect two of the ports 55 11 in the closed side of the revolving wheel, and at the terminals of the grooves 33, the said ring is provided with the inner peripheral steam ports 34, that are adapted to be brought into a registering position with the

peripheral steam recesses 29, formed in the central bearing disk 28. The adjustable valve ring 32, has attached to one side thereof the off-standing fixed lever arm 35, in which is 70 pivotally mounted the spring actuated catch lever 36, the inner end of which is adapted to engage the catch notches 37, formed in the outer face or side of the disk 28, to hold the ring 32, stationary in its adjusted position. 75

By the adjustment of the valve ring 32, it will be obvious that the same may be brought to a position to carry either of the ports at the extremities of the steam grooves 33, to a registering position with the opposite recesses 29, 80 of the disk 28, in order to quickly reverse or change the rotation of the cylinder wheel, while at the same time the said valve ring may be adjusted to regulate the quantity of steam admitted to and exhausted from the 85 steam cylinders in order to control the speed of the engine or to entirely cut off the supply of steam thereto. The said valve ring therefore provides the engine with every necessary adjustment to completely control the operation thereof. It is to be noted that the stationary crank or crank pin of the crank shaft is eccentric to the center of the revolving wheel, and the steam grooves 33, are located diametrically opposite each other directly 90 above and below such crank pin so that the uppermost pair of cylinders will be receiving live steam while the corresponding lower pair of cylinders are exhausting steam.

From the above it is thought that the construction, operation and many advantages of the herein-described steam engine will be readily apparent to those skilled in the art, and it will be understood that changes in the form, proportion and the minor details of construction, may be resorted to without departing from the principle or sacrificing any of the advantages of this invention.

Having thus described the invention, what is claimed, and desired to be secured by Letters Patent, is—

1. In a steam engine, the combination of a bearing bracket provided with opposite parallel bearing arms, a stationary crank detachably fastened to one of the bearing arms of 115 said bearing bracket, a stationary bearing sleeve removably mounted on the other bearing arm of said bracket opposite the said stationary crank, a revolving cylinder wheel mounted at one side on the stationary crank 120 and provided at its opposite side with a bearing trunnion mounted in said stationary bearing sleeve, a series of radial steam cylinders mounted within said wheel and having their pistons connected with said crank, and valve 125 devices for said cylinders, substantially as set forth.

2. In a steam engine, the combination of a bearing bracket provided with opposite parallel bearing arms having squared sockets at 130 their upper ends, a revolving cylinder wheel mounted to rotate between said bearing arms

and provided at one side with a central bearing trunnion, a stationary bearing sleeve fitted in the socket of one of said bearing arms and receiving said trunnion, a stationary crank shaft projecting centrally through one side of said wheel and provided at its inner end with a fixed crank pin, the cylinders mounted radially within said wheel and having their pistons connected with said 10 crank pin, a squared shaft block fitted on the outer end of said crank shaft and resting in the squared socket of one of said bearing arms, means for clamping said shaft block to the adjacent bearing arms, and a valve device 15 for said cylinders, substantially as set forth.

3. In a steam engine, the combination of a fixed or stationary crank, a cylinder or casing wheel mounted to rotate over said crank and open at one side, a series of radially disposed steam cylinders arranged within said 20 wheel, segmental clamp plates interposed between and binding at their ends against said cylinders to hold the same in position, a removable side cap plate inclosing the open 25 side of the wheel, and having a central bearing opening for the fixed crank, the piston heads moving within said cylinders and having their rods connected with said crank, and a valve device for said cylinders, substantially as set forth.

4. In a steam engine, the combination of the stationary crank, a cylinder wheel mounted to rotate over said crank and provided in one side with steam ports, a series of radial 35 steam cylinders mounted within said wheel and having their pistons connected with said cranks and provided with steam ports in their closed ends, channel plates interposed between the cylinders and one side of the wheel 40 to connect the ports of the cylinders with those in the wheel, and a stationary adjustable valve device arranged at one side of the

wheel over the ports thereof, substantially as set forth.

5. In a steam engine, the combination of a 45 revolving cylinder wheel carrying a series of actuating steam cylinders and provided in one side with steam ports communicating with the cylinder ports, a stationary bearing disk provided with opposite live and exhaust 50 steam recesses, and an adjustable valve ring mounted to work over said bearing disk at one side of said wheel and provided with steam grooves adapted to connect two ports of the wheel and inner peripheral ports at 55 the terminals of said grooves adapted to register with the steam recesses of said bearing disk, substantially as set forth.

6. In a steam engine, the combination of a revolving cylinder wheel carrying a series of 60 actuating steam cylinders and provided in one side with steam ports communicating with the cylinder ports, a peripherally beveled stationary bearing disk arranged at one side of the wheel and provided in its periphery 65 with directly opposite live and exhaust steam recesses, an adjustable valve ring having an inner reversely beveled periphery working over said stationary bearing disk, diametrically opposite segmental steam grooves in its 70 inner side, and inner peripheral steam ports at the terminals of said grooves to register with the recesses of said stationary bearing disk, and a lever catch-device for said valve ring to hold the same stationary in its adjusted 75 position, substantially as set forth.

In testimony that I claim the foregoing as my own I have hereto affixed my signature in the presence of two witnesses.

HERMAN NIELSEN.
